[57] CLAIM

The ornamental design for a trim piece for an automobile hood, as shown and described.

DESCRIPTION

FIG. 1 is a top plan view of a trim piece for an automobile hood showing our new design;

FIG. 2 is a front elevational view thereof;

FIG. 3 is a rear elevational view thereof;

FIG. 4 is an enlarged end elevational view thereof;

FIG. 5 is a front elevational view of a trim piece for an automobile hood on a reduced scale showing our new design, it being understood that the broken lines are for illustrative purposes only.

FIG. 1

FIG. 2

FIG. 3

FIG. 4

FIG. 5
